UNITED STATES PATENT OFFICE.

JAMES S. THOMPSON, OF PELHAM, NEW YORK.

PERMANENT MOLD FOR MAKING CASTINGS.

Application filed August 11, 1924. Serial No. 731,243.

The object of this invention is, generally, to simplify and improve the means for casting in permanent molds, whereby the operation is greatly simplified and facilitated and is enabled to be carried on with a greater degree of efficiency and at a much lower maintenance and operating cost than has been possible heretofore.

Another object of the invention is to produce in a permanent mold a uniformly better casting than has been customary heretofore by providing a more efficient mold of simpler construction adapted for a greater variety of work than is known in the art, so far as I am aware, whereby a clean casting of desired texture and proper size and shape, free from blow-holes, fins and other such imperfections, may be uniformly produced in condition for the intended use without the necessity of subjecting the casting to any finishing operation.

Another object of the invention is to provide a permanent mold which easily can be adapted to produce castings of different sizes and shapes by changing one part thereof, and enabling this change to be made in a simple and expeditious manner so that a plurality of molds laid out on a floor in a foundry may be quickly changed to produce one casting or another, as and whenever desired.

Another object of the invention is to provide the drag or relatively fixed member of the mold with a removable liner containing a portion of the mold cavity, and to construct the liner and the drag so that a plurality of different liners may be used selectively in the same drag for making correspondingly different castings.

Another object of the invention is to provide a removable pouring gate adapted to be rigidly held in place during the pouring operation and forming one end of a permanent mold for covering the opening to the mold cavity; and also to arrange this pouring gate to engage the drag liner for the purpose of registering the drag liner lengthwise in the mold and against the end wall of the cope whereby, when the pouring gate is arranged in place, it will be in operative contact with the drag liner and the cope and will hold the drag liner against the opposite end of the cope.

Another object of the invention is to provide a sand core for use in connection with

the gate to form an end wall of the mold cavity, whereby the connection of the sprue with the casting is reduced in size and spaced from the margin of the end of the casting so that the sprue can be readily and easily knocked off the casting when the latter is removed from the mold without damaging the casting; and also whereby the mold, while sufficiently rigid to hold the molten metal in the mold cavity for producing the desired smooth and properly formed casting, is capable of such flexibility that it can be maintained in practically continuous use without liability of sticking or binding and with the casting easily removable therefrom.

Further objects of the invention are to provide a permanent mold having the cope pivotally connected to the drag and a removable pouring gate disposed opposite to said pivot and adapted to close one end of the mold cavity and hold the parts of the mold together during the casting operation; to make the gate wedge-shaped so that it may adjust itself to relieve any expansion that may take place in the mold during continued use thereof; to provide a gate core which will not only protect the end of the mold against the cutting action of the molten metal, but which will also prevent the movable part of the mold from sticking to the relatively fixed part, which may result from shrinking, pinching or expanding during the casting operation; to space the drag liner from the walls of the drag to permit access thereto easily for removal and replacement, and also to provide an air space around the liner for ventilating purposes; to provide for centering and locking the liner rigidly in place in the drag in a simple and efficient manner; to provide for the replacement of that portion of the mold cavity wall against which the stream of molten metal is initially directed whenever said wall becomes damaged in actual use; and to provide means whereby a pattern number or other identification mark may be applied to the casting when it is made and for easily changing this mark whenever required.

My invention also has for its object to provide a permanent mold especially adapted for making brake shoes and having all of the advantages and producing all of the results hereinbefore mentioned, and also for

locating the connection of the sprue with the end of the shoe casting below the top of the shoe to produce a clean and properly shaped end stop.

In the accompanying drawings I have illustrated a selected embodiment of the invention for use in casting brake shoes because that is an embodiment which I have practically and successfully tested and demonstrated and because it illustrates very clearly the objects and uses of my invention. It will be understood, however, that this selection is for purposes of illustration and description and is not intended to be understood as a limitation or restriction of the invention which is or may be adapted for other molds for making a variety of different castings.

In the drawings,

Fig. 1 is a side elevation of a mold for making a brake shoe and embodying the invention;

Fig. 2 is a top plan view of the mold shown in Fig. 1;

Fig. 3 is a front end elevation of the mold;

Fig. 4 is a sectional view on the line 4—4 of Fig. 1;

Fig. 5 is a longitudinal sectional view on the line 5—5 of Fig. 2;

Fig. 6 is a top plan view of the drag or relatively fixed member with the pouring gate removed;

Fig. 7 is a perspective view of a solid metal drag liner;

Fig. 8 is a perspective view of the pouring gate;

Fig. 9 is a transverse sectional view on the line 9—9 of Fig. 1;

Fig. 10 is a longitudinal sectional view of a drag liner having the mold cavity wall formed partly of refractory material;

Fig. 11 is a longitudinal sectional view similar to Fig. 5 showing the mold cavity walls made of refractory material;

Fig. 12 is a transverse sectional view on the line 12—12 of Fig. 5;

Figs. 13 and 14 are views similar to Fig. 12 showing different drag liners for making brake shoes varying in size from that shown in Fig. 12.

Fig. 15 is a detail sectional view showing a novel manner of securing a removable refractory plug in the mold.

Referring to the drawings the mold comprises a drag 15 and a cope 16 having a mold cavity 17 therein adapted for casting a brake shoe. The cope is pivotally connected to the drag opposite the pouring gate by means which will permit the cope to be moved rectilinearly from the drag for a limited distance and then be swung on said pivot to an open position to permit removal of the casting and for other purposes. This operating mechanism is fully set forth in

my companion application filed concurrently herewith (Patent No. 1,552,247, September 1, 1925), and it is believed sufficient for the purposes of this application to indicate that on each side of the mold there is a bell crank lever pivoted to a stud on the drag by a pin 19, the lever comprising an upwardly directed arm 20 which constitutes a part of the operating lever, and a horizontal arm 21 which is provided with a slot 22 and is engaged with a pin 23 on the rear end 24 of the cope.

The drag comprises a shell 25 made more or less in skeleton form to reduce weight and to provide for the circulation of air, and this shell is adapted to receive a drag liner 26 which is one of a plurality adapted to be easily inserted in and removed from the shell. Each drag liner is made of a size and shape to fit properly in the shell, but that portion of the mold cavity ordinarily located in the drag of a mold and here located in the drag liner may be varied in size and shape to cooperate with a standard mold cavity section in the cope for the production of a variety of different castings. For example, in Figs. 5 and 12 the mold cavity 17 is formed partly in the drag liner and partly in the cope, and it is shaped to provide a brake shoe of a certain size. In Fig. 13 a drag liner 26' is shown adapted for cooperation with the same cope shown in Fig. 2, but sized and shaped to produce a somewhat larger brake shoe; and in Fig. 14 is shown a drag liner 26'' for cooperating with the same cope shown in Figs. 12 and 13 to produce a still larger brake shoe. Thus the mold can be changed from time to time as required to produce brake shoes of different sizes, and of the same type, by simply changing the drag liner, and this is easy to do as will hereinafter appear. This provision for substitution of drag liners to produce shoes of different sizes may be carried farther than I have shown, but it is believed that Figs. 12 to 14 showing three different drag liners for use with the same cope and drag shell will be sufficient to indicate the possibilities which my invention presents for making a great variety of brake shoes in the same mold.

I may employ a drag liner having the mold cavity walls formed entirely of metal as shown in Fig. 7 or I may employ a drag liner having the mold cavity walls formed partly of refractory material 27 and partly of metal 28, 41, as shown in Fig. 10; or the walls of the mold cavity may be all refractory in the drag liner, as shown at 29 in Fig. 11. The walls of the mold cavity in the cope may be all metal as shown in Figs. 5, 12, 13 and 14, or they may be formed with refractory material 30, as shown in Fig. 11. It is believed that these examples of the different ways in which the mold cavity walls

may be formed will be sufficiently illustrative to indicate that many variations may be made without departing from the invention, and I may say generally that I 5 contemplate employing the invention with molds having cavity walls all metal, all refractory or part metal and part refractory in whatever combinations and arrangements may be desirable for particular castings.

10 In the construction shown, the drag liner is arranged to rest at its ends 31 upon the drag shell. The depending end 24 of the cope abuts against the rear end of the drag liner to close the rear end of the mold cavity. The front end of the cope is flush with the front end of the drag liner and this end of the mold cavity is exposed. A removable pouring gate 32 is arranged to be supported in position at the forward end 15 of the mold by a support 33 which is bolted or otherwise secured to the forward end of the drag. This pouring gate is generally wedge-shaped and is provided on its back with a rib 32' which engages a projection 33' on the support 33. The rib and projection form what may be termed a point contact for the pouring gate with its support which is amply sufficient to keep the pouring gate in proper position in the mold, 20 while at the same time it facilitates positioning the gate in the mold and removing the gate from the mold. The gate fits snugly between the cope and drag and the support, and that face which engages the cope and drag is flat and smooth to avoid cracks and crevices into which the molten metal may run and provide fins and projections which are undesirable. The support 33 is recessed at 34 to receive the 25 tapered lower end 32" of the pouring gate, and the construction is such that the lower end of the pouring gate will fit snugly in this recess against the drag liner, while the upper portion of the pouring gate will fit snugly against the cope, and the gate will be held in this position by its wedge-shaped engagement with the lower end of the support and by the engagement of the projection 33' with the rib 32'. The cavity 35 in 30 the pouring gate tapers downwardly to register at its lower end with the adjacent end of the mold cavity. The gate is provided with a lip 36 at the top of the rib 32' which projects over the support 33 and forms a sort of handle for positioning the gate and a projection which can be struck with a tool to loosen the gate in event any part of the mold tends to stick. The cavity 35 is continued in the form of a groove at the top 35 of this lip 36 so that if more metal is poured into the mold than the mold cavity and the gate cavity will hold, the excess metal will overflow the gate through the groove 35' and fall upon the floor clear of all parts of the mold, thereby avoiding the trouble and

annoyance which might result if the excess metal overflowed upon parts of the mold.

A core 37 is arranged in the cavity of the pouring gate and against the ends of the cope and the drag liner. This core may be 70 conveniently made of sand, like, or substantially like, hard sand cores as are customarily made in foundry practice. The core is comparatively thin and tapers both in width and in thickness from its top to its bottom 75 to fit snugly in the mold cavity and against the cope and drag liner. The side walls of the core are preferably tapered to fit in the pouring gate cavity. The lower end of the core terminates above the bottom of the 80 pouring gate cavity and projects below the top of the mold cavity at the forward end thereof so that the discharge of the pouring gate cavity into the mold cavity at 35" is located at or about centrally of the end of 85 the mold cavity so that, when the casting is removed from the mold, the sprue will be connected with the casting at the end thereof and at or about centrally of the end and at some distance from the margin of the 90 end. I have found in practice that this sprue can be easily knocked off of the casting by a comparatively light blow immediately after the casting is removed from the mold. This can be done without breaking 95 the corners or margin or otherwise damaging the casting, and as a general rule only a slight protuberance is left on the end of the casting. This protuberance is not objectionable in a brake shoe casting, but in any 100 casting it can be easily removed by a little grinding or chipping.

The pouring gate core is not absolutely necessary for the successful use of a permanent mold embodying my invention, but I 105 have found it desirable because it serves many useful purposes. I have already pointed out that it serves to restrict the discharge of the pouring gate cavity and I may say further that when the casting is removed 110 from the mold, that portion of the core which is located opposite the end of the mold cavity will remain in the recess, which it forms, between the end of the shoe casting and the sprue, even though the remainder 115 of the core is broken in opening the mold. The core also protects the end of the cope, with which the molten metal would otherwise contact, from the cutting action of the molten metal in pouring; it relieves any 120 tendency of the cope to stick after the metal has been poured, which may be due to shrinking, pinching or expanding of the parts of the mold; and it also assists in preventing runs of the molten metal from between the 125 pouring gate and the other parts of the mold. In practice, it has been customary to slip the core into place in the pouring gate after the latter has been positioned in the mold. However, in Fig. 11 the mold is 130

shown without the core to indicate that it is not indispensable under all conditions, even though, as at present advised, I believe it is a desirable feature of the mold.

5 It is desirable to provide that the drag liner may be inserted in and removed from the drag shell easily and quickly, even when heated by repeated casting operations, and this is made possible with my invention in
 10 a very simple manner by recessing the inner sides of the shell at 38 to space the liner from the sides of the shell and providing these sides with guides 39 midway between their ends to form wedge-shaped guideways
 15 39' for the wedge-shaped lugs 40 on the sides of the liner (Figs. 6, 7). In the practical use of this invention I have made the guide lugs of a size to fit snugly between the sides of the shell but with some degree of looseness
 20 between the lugs 39 so that the liner is capable of a little adjustment lengthwise of the shell. The drag liner can be easily removed from the drag shell by inserting the prongs of tongs in the recesses 38 to engage
 25 the underside of the drag liner, whereupon the drag liner may be lifted out of the shell and another drag liner similarly engaged may be replaced in the shell.

To protect the drag liner against the cutting action of the molten metal as it enters the mold cavity, I have found it desirable to provide a renewable section 41 (Fig. 5) in the bottom wall of the mold cavity at the end thereof adjacent the pouring gate. This renewable section is preferably made of some heat resistant metal and it may be conveniently secured in place by a bolt 42 passing through the drag liner from the bottom thereof.

40 A modern brake shoe is generally provided with a reinforcing back and a steel lug, which are embedded in the shoe during the casting operation. The cope is provided with a recess 17' to receive the steel lug and the core therefor (not shown) and this recess may be formed in a plug 43 (Fig. 5) which is removably secured in a tapered opening 44 in the cope by means of bolts 45 and cross-pieces 46. The steel back (not shown), which is supported in the mold cavity for embedment in the back of the shoe casting, may be held in place for the casting operation by supporting devices engaged therewith and entering openings 47 in the plug. Vents 47' may also be provided in the plug, or the openings 47 may be made sufficiently large for this purpose. The plug 43 may be made of metal (Figs. 5, 12, 13, 14) and instead of being removable it may be an integral part of the cope; or the plug may be made of refractory material (Fig. 11). So far as the present invention is concerned, these features of the mold may be varied in many ways, some of which are set forth in my Patents No. 1,484,421 to No. 65

1,484,438, inclusive, and also in my pending applications Serial No. 727,100 and Serial No. 727,101, filed July 21, 1924. In Fig. 15 I have shown the refractory plug 43' adapted to be secured in the opening 44 in the 70
scope by a bolt 45' which engages the cross-piece 46''. The head 45'' of the bolt is engaged with the refractory plug and the nut 46''' engages the cross-piece. The bolt has a vent opening 47'' extending therethrough. 75

The cope should fit snugly upon the drag liner during the casting operation to prevent runs of the molten metal therebetween. I have not found it necessary to provide any means for locking the cope to the drag, because the weight of the cope will ordinarily resist any tendency of the cope to open during the casting operation. I think it best to permit that degree of flexibility which is afforded by relying upon the weight of the cope to hold it in closed position, because if any unusual amount of gas is produced during the casting operation or the vents become plugged, or anything else happens which would tend to lift the cope, it will simply lift and accommodate itself to these unusual circumstances. In such case, the casting may be unfit for use, but it is more important that the mold is not damaged, for when the casting is removed, the mold can be made ready again for another casting operation.

I desire to have the cope register properly upon the drag liner and fit snugly thereon when it comes to closed position and 100 without the necessity of any manual manipulation or adjustment. To this end I provide the cope with tapered lugs 48 to engage beveled seats 49 on the drag liner (Figs. 7, 9). I prefer to provide two of 105 these tapered lugs at each side of the cope, adjacent the ends thereof, and an equal number of beveled seats correspondingly disposed in the upper edges of the drag liner, so that when the cope is lowered into position upon the drag liner, the lugs 48 engaging the beveled seats 49 will register the 110 cope and the drag liner with each other so that the cope will fit snugly in its proper position upon the drag liner (Fig. 9). 115 When the mold is closed by lowering the cope to its seat on the drag liner and the pouring gate is placed in position the liner will be held rigidly between the depending rear end of the cope and the gate, and inserting the gate will position the liner in the shell. If necessary the gate can be 120 tapped with a tool to force it into place.

In casting brake shoes it is customary to place a pattern number or other identification mark on one of the end stops of the shoe, and I provide a plate 50 (Fig. 5), which is preferably wedge-shaped and is adapted to be removably secured in a wedge-shaped opening 51 adjacent the cope end 24 125 12

by a bolt 52. The lower end 50' of this plate projects into the recess 17 of the mold cavity 17', which is provided to form one end stop of the brake shoe, and this end of 5 the plate is provided with characters to cast numbers, patent marks or other identification marks on the shoe during the casting operation. This plate projects above the cope and is provided with an eye 53 so that 10 it can be readily changed when the drag liner is changed.

Instead of the plate 50 at the rear end of the cope I may provide an identification plate 54 in a recess 55 in the front end of 15 the cope and hold this plate removably in operative position by means of a locking device 56 secured to the cope by a bolt 57 and having a projection 58 to engage the top of the plate. I prefer the identification 20 plate 50 (Fig. 5) because the plate 54 (Fig. 11) is comparatively thin and may become sufficiently distorted by the heat of the molten metal to cause parts of the mold to stick in use, particularly if a sand core is 25 not used in the pouring gate; and even if a core is used to protect this plate which forms the front or part of the front end of the cope. The plate 50 is rigidly held in a substantially wedge-shaped opening formed 30 wholly within the cope and cannot become distorted or cause parts of the mold to stick. The impression face 50' of the plate 50 may possibly be affected by the heat but it cannot become so distorted as to cause parts of 35 the mold to stick or interfere with the operation thereof.

My present invention is the result of a thorough knowledge of foundry practice and a very careful investigation and study of the difficulties encountered in the use of permanent molds for making castings of different kinds, sizes and character on a commercial scale. It has been my object to produce a mold which can be used continuously 45 for a full day, and day after day, in commercial practice for making castings of such perfection that they can be put at once into commercial use without any, or at least with very little, finishing work thereon; and also 50 to produce a mold which can be rapidly and easily operated to reduce the labor and the cost. I have accomplished these results with this invention, and I have successfully demonstrated every feature of the invention 55 in practical foundry practice under the usual conditions which prevail. I appreciate that the mold as herein shown, adapted for making brake shoes of a well-known type, may be refined for this purpose, and also changed 60 and refined to adapt it for making other castings, by improvements which may or may not amount to invention, but I believe that in every case the basic principles of this invention will always be found desirable 65 in any modifications, improvements or re-

finements of the mold for making brake shoes or other castings.

My invention simplifies the labor connected with a casting operation in foundry practice and enables castings to be made under 70 much pleasanter conditions than have heretofore prevailed. I have found it especially convenient to provide the interchangeable drag liners because it enables a variety of 75 shoes or other castings to be made by a quick 80 change of the liners without necessitating a change of mold lay-outs on the floor. This change can be accomplished without delaying the casting operations and with very little labor. This is an important feature of 85 the invention because many castings, such as brake shoes, are made in many sizes or varieties of a single type and the change from one size or variety to another can be effected by simply changing the drag liner. 90 Thus it will be seen that the provision of means for the manufacture of different lots of shoes or other castings without changing the lay-out on the floor and without delaying the casting operation or interfering with 95 the work of the operators will result in a great saving in time and labor.

I find it convenient to make the drag shell in skeleton form partly to lighten it and partly to ventilate the mold to reduce the 95 heat during continuous molding operations and to prevent the possible sticking of the parts. I have provided this construction also to enable the use of tongs for the insertion and removal of the drag liner. 100

I am aware that changes in the form, construction and arrangement of parts may be desirable or necessary to adapt the invention for different castings or to meet different conditions and I consider myself entitled to 105 make all such changes as fairly fall within the scope of the accompanying claims.

I claim:

1. A permanent mold for making castings and comprising two members having a mold cavity therein, one of said members being in the form of a shell, and a liner removably seated in said shell and containing a portion of the mold cavity. 110

2. A permanent mold for making castings and comprising two members having a mold cavity therein, one of said members being in the form of a skeleton shell, and a liner removably seated in said shell and containing a portion of the mold cavity. 115

3. A permanent mold for making castings and comprising two members having a mold cavity therein, one of said members being in the form of a shell, and a liner containing a portion of the mold cavity and removably seated in the shell and having portions thereof spaced from the shell. 120

4. A permanent mold for making castings and comprising two members having a mold cavity therein, one of said members being in 125

the form of a skeleton shell having openings therein, and a liner containing a portion of the mold cavity and removably seated in the shell and having portions thereof spaced 6 from the shell.

5. A permanent mold for making castings and comprising two members having a mold cavity therein, one of said members being in the form of a shell recessed interiorly 10 at its sides and provided with openings, and a liner containing a portion of the mold cavity and removably seated in the shell.

6. A permanent mold for making castings and comprising two members having a mold 15 cavity therein, one of said members being in the form of a shell, a liner containing a portion of the mold cavity and removably seated in the shell, and means for centering the liner in the shell.

20 7. A permanent mold for making castings and comprising two members having a mold cavity therein, one of said members being in the form of a shell, a liner containing a portion of the mold cavity and removably seated 25 in the shell, and interengaging guiding means on the shell and liner.

8. A permanent mold for making castings and comprising two members having a mold cavity therein, one of said members being in 30 the form of a shell, a liner containing a portion of the mold cavity and removably seated in the shell, and wedge-shaped guiding means on the shell and liner.

25 9. A permanent mold for making castings and comprising two members having a mold cavity therein, one of said members being in the form of a shell having vertically disposed guideways in its sides, and a liner containing a portion of the mold cavity and removably seated in the shell and having lugs 40 on its sides to engage said guideways.

10. A permanent mold for making castings and comprising two members having a mold cavity therein, one of said members being in the form of a shell having recesses 45 in each side thereof and guideways between said recesses, and a liner containing a portion of the mold cavity and removably seated in the shell and having lugs on its 50 sides to engage said guideways.

11. A permanent mold for making castings and comprising two members having a mold cavity therein, one of said members being in the form of a shell having openings 55 in its bottom and recesses in its sides, a liner containing a portion of the mold cavity and removably seated in the shell, the openings and recesses providing space for tongs in inserting the liner in and removing it from the 60 shell, and interengaging means on the shell and liner.

12. A permanent mold for making castings and comprising two members having a mold cavity therein, one of said members being pivotally engaged with the other 65

member and having an end forming an end wall for the mold cavity, said other member being in the form of a shell, and a liner containing a portion of the mold cavity and removably seated in the shell with one end 70 abutting against said end wall.

13. A permanent mold for making castings and comprising a drag and a cope having a mold cavity therein, said drag being in the form of a shell having recesses in its 75 sides, the cope being pivotally engaged with the drag and having an end forming an end wall for the mold cavity, a liner containing a portion of the mold cavity and removably seated in the shell with its end abutting said 80 end wall, and interengaging means on the shell and liner.

14. A permanent mold for making castings and comprising two members having a mold cavity therein open at one end, a support on one of the said members, and a removable pouring gate engaged with said support and abutting the ends of said members, said pouring gate covering the open 85 end of the mold cavity and having its pouring cavity in communication with the mold cavity.

15. A permanent mold for making castings and comprising two members having a mold cavity therein opening through one end 90 of said members, a support on one member, and a removable pouring gate engaged with said support and abutting said end of the members, said pouring gate covering said open end of the mold cavity and having its 95 pouring cavity in communication with the open end of the mold cavity.

16. A permanent mold for making castings and comprising two members having a mold cavity therein opening through one 100 end of said members, a support on one member, and a wedge-shaped pouring gate engaged with said support and the end of said members and having its 105 pouring cavity communicating with the mold cavity. 110

17. A permanent mold for making castings and comprising two members having a mold cavity therein, a support on one member having a projection, and a wedge-shaped pouring gate engaged with said projection 115 and with the ends of said members and having its pouring cavity communicating with the mold cavity.

18. A permanent mold for making castings and comprising two members having a mold cavity therein, an inclined support on one member, and a wedge-shaped pouring gate open at one side and adapted to be positioned between the support and the end 120 of said members with its open side abutting the members and its pouring cavity communicating with the mold cavity. 125

19. A permanent mold for making castings and comprising two members having a mold cavity therein, a support on one mem- 130

- ber having a projection, and a wedge-shaped gate positioned between said support and the end of said members and having a rib to engage said projection.
- 5 20. A permanent mold for making castings and comprising two members having a mold cavity therein, and an inclined support on one member, a wedge-shaped pouring gate open at one side arranged to be positioned between the support and the end of said members with its open side abutting the members and its pouring cavity communicating with the mold cavity, said support having a projection and said pouring gate having a rib to engage said projection.
- 10 21. A permanent mold for making castings and comprising two members having a mold cavity therein, a removable pouring gate, and means for securing the pouring gate in position against the members with the pouring cavity communicating with the mold cavity, said pouring gate having a lip with a groove therein to permit the escape of excess metal without dripping on the mold.
- 15 22. A permanent mold for making castings and comprising a drag and a cope having a mold cavity therein, the cope being pivoted to the drag at one end thereof, a support at the other end of the drag, and a removable pouring gate engaged with said support and abutting the adjacent end of the drag and cope with its pouring cavity communicating with the mold cavity.
- 20 23. A permanent mold for making castings and comprising a drag and a cope having a mold cavity therein, the cope being pivoted to the drag at one end thereof, an inclined support at the other end of the drag, and a removable wedge-shaped pouring gate engaged with said support and with the adjacent end of the drag and cope and having its pouring cavity communicating with the mold cavity.
- 25 24. A permanent mold for making castings and comprising a drag and a cope having a mold cavity therein, the cope having an end wall extending over one end of the mold cavity and pivotally engaged with the drag, a support at the other end of the drag inclined relatively to said end, and a wedge-shaped pouring gate engaging said support and abutting the end of said members and having a pouring cavity communicating with said mold cavity.
- 30 25. A permanent mold for making castings and comprising a drag and a cope having a mold cavity therein, the cope being pivoted to the drag at one end thereof, a support at the other end of the drag inclined relatively to said end and forming with the end a seat for the pouring gate, and a wedge-shaped pouring gate positioned in the seat formed between the support and the adjacent end of the drag and abutting the
- end of the drag and cope and having its pouring cavity communicating with the mold cavity.
- 35 26. A permanent mold for making castings and comprising a drag and a cope having a mold cavity therein open at one end, a pouring gate at the open end of the mold cavity and having its pouring cavity communicating with the mold cavity, and a core arranged in the pouring gate between the pouring cavity and the end of the cope to protect the cope against the cutting or burning action of the molten metal.
- 40 27. A permanent mold for making castings and having a mold cavity therein open at one end, a pouring gate removably engaged with the mold and covering the open end of the mold cavity with its pouring cavity communicating with the mold cavity, and a core supported in the pouring gate against the end of the mold.
- 45 28. A permanent mold for making castings and having a mold cavity therein, a removable pouring gate open on one side and having its open side abutting the end of the mold with the pouring cavity communicating with the mold cavity, and a core arranged in the pouring gate and held thereby against the end of the mold.
- 50 29. A permanent mold for making castings and comprising a drag and a cope having a mold cavity therein, a support at one end of the drag, a wedge-shaped pouring gate engaged with said support and having its pouring cavity communicating with the mold cavity, and a core held by the pouring gate against the end of the mold.
- 55 30. A permanent mold for making castings and having a mold cavity therein opening through the mold, a pouring gate arranged with its pouring cavity communicating with the mold cavity, and a core arranged between the pouring gate and the mold and forming with the pouring gate a pouring cavity tapering to the mold cavity.
- 60 31. A permanent mold for making castings and having a mold cavity therein opening through one end of the mold, a removable pouring gate having its pouring cavity communicating with the mold cavity, and a core arranged between the pouring gate and the mold and partly covering the open end of the mold cavity.
- 65 32. A permanent mold for making castings and having a mold cavity therein opening through the mold, a pouring gate open at one side and arranged with its open side abutting the end of the mold and with its pouring cavity communicating with the mold cavity, and a core held by the pouring gate against the end of the mold and partly covering the open end of the mold cavity.
- 70 33. A permanent mold for making castings and comprising a drag and a cope having a mold cavity therein open at one end,

3. A removable pouring gate supported in position at the open end of the mold, and a removable core adapted to be inserted in the pouring gate against the cope to protect the cope against the cutting or burning action of the molten metal and forming with the pouring gate a tapering pouring cavity which discharges into the mold cavity.
34. A permanent mold for making castings and comprising a drag and a cope having a mold cavity therein open at one end, a pouring gate open on one side and removably supported at the open end of the mold, and a comparatively thin tapering core arranged between the pouring gate and the cope and forming a facing for the end of cope to protect it against the cutting or burning action of the molten metal and also forming with the pouring gate a tapering pouring cavity which discharges into the mold cavity.
35. A permanent mold for making castings and comprising two members having a mold cavity therein, one of said members being in the form of a shell, a liner removably seated in the shell and having beveled seats, the other member having tapered lugs to engage said beveled seats for registering the members.
36. A permanent mold for making castings and comprising two members having a mold cavity therein, a pouring gate having its pouring cavity communicating with said mold cavity, and a removable heat resisting section in the wall of the mold cavity where the molten metal first engages when it enters said mold cavity.
37. A permanent mold for making castings and comprising a drag and a cope having a mold cavity therein, a pouring gate having its pouring cavity communicating with the mold cavity, said drag having a removable section in the wall of the mold cavity which the molten metal engages when it enters the mold cavity.
38. A permanent mold for making castings and comprising two members having a mold cavity therein open at one end, a pouring gate having its pouring cavity arranged to discharge into the open end of the mold cavity, and a heat resisting section in the bottom of the mold cavity which the molten metal engages when it enters the mold cavity.
39. A permanent mold for making castings and comprising two members having a mold cavity therein, one of said members having a removable liner arranged to abut at one end against the other member, and a removable pouring gate adapted to be engaged with said members and the other end of said liner to secure the liner rigidly in place for the casting operation.
40. A permanent mold for making castings and comprising two members having a mold cavity therein, one of said members
5. the cope against the cutting or burning action of the molten metal and forming with the pouring gate a tapering pouring cavity which discharges into the mold cavity.
10. 15. 20. 25. 30. 35. 40. 45. 50. 55. 60. 65. 70. 75. 80. 85. 90. 95. 100. 105. 110. 115. 120. 125.
- mold cavity therein, one of said members having a portion thereof forming an end wall of the mold cavity and the other member having a movable liner arranged to abut at one end against said portion of the other member, and a removable pouring gate adapted to be engaged with said liner for securing the liner in fixed position during the casting operation.
41. A permanent mold for making castings and comprising two members having a mold cavity therein, one of said members having a depending end and the other member having a movable liner arranged to abut at one end against said depending end, and a removable pouring gate adapted to be engaged with said liner to hold it in fixed position between said depending end and the pouring gate during the casting operation.
42. A permanent mold for making castings and comprising two members having a mold cavity therein open at one end, one of said members having a movable liner abutting at one end against the other member, and a removable pouring gate covering the open end of said mold cavity and engaging the other end of the liner to hold the liner rigidly in place during the casting operation.
43. A permanent mold for making castings and comprising two members having a mold cavity therein, one of said members having a rigid end and the other member having a movable liner which abuts at one end against said rigid end, and a removable pouring gate adapted to engage the other end of said liner to hold the liner in fixed position between said rigid end and the pouring gate during the casting operation.
44. A permanent mold for making castings and comprising two members having a mold cavity therein, an endwise movable liner in one of said members, and means for adjusting and holding said liner in fixed position for the casting operation.
45. A permanent mold for making castings and comprising two members having a mold cavity therein, one of said members being in the form of a shell, a plurality of interchangeable liners adapted to be selectively arranged in said shell, and means for securing the liner rigidly in the shell for the casting operation.
46. In a permanent mold for making castings, a member comprising a shell, a removable liner for said shell having a part of the mold cavity therein, and a section of refractory material seated in the liner to form a wall of the mold cavity.
47. In a permanent mold for making castings, a member comprising a shell, a removable liner for said shell having a mold cavity therein and a recess extending lengthwise of the liner and spaced from the ends thereof, and a section of refractory material

seated in said recess and forming with the ends of the liner a composite refractory and metal wall for the mold cavity.

48. A permanent mold for making castings having a mold cavity therein and an opening communicating with said cavity, a refractory plug removably seated in the opening, and means comprising a bolt extending through said plug for securing the 10 plug in the opening.

49. A permanent mold for making castings having a mold cavity therein and an opening communicating with said cavity, a refractory plug removably seated in the 15 opening, means comprising a cross-piece extending across the opening and engaging the mold, and a bolt engaging the plug and said cross-piece for securing the plug in the opening.

50. A permanent mold for making castings having a mold cavity therein and an opening communicating with said cavity, a refractory plug removably seated in the opening, means comprising a bolt extending through the plug for securing the plug in 25 the opening, said bolt having a vent opening extending therethrough.

51. A permanent mold for making castings having a mold cavity therein and an opening communicating with said cavity, a refractory plug removably seated in the opening, means comprising a cross-piece extending across the opening and engaging the mold, a bolt extending through the plug and the cross-piece and having its head engaged 30 with the plug, and a nut on the bolt engaging the cross-piece.

JAMES S. THOMPSON.
